W. M. WEEKS

BOTTLE CLOSURE

Filed Aug. 7, 1926

Inventor.
Wallace M. Weeks.
By Harry De Wallace
Attorney.

Patented Apr. 19, 1927.

UNITED STATES PATENT OFFICE.

WALLACE M. WEEKS, OF SKANEATELES, NEW YORK, ASSIGNOR OF ONE-HALF TO
JOHN A. PEASE, OF SKANEATELES, NEW YORK.

BOTTLE CLOSURE.

Application filed August 7, 1926. Serial No. 127,869.

This invention relates to improvements in bottle closures, particularly of the type employed for closing and sealing milk bottles and the like, and has for its object to provide a closure for liquid and other containers of novel, simple and inexpensive construction, which is highly effective for sealing, as well as for rendering the pouring mouth of a container sanitary. A particular object is to provide a bottle closure formed with a plane disc stopper adapted to be tightly seated in the recess of the bottle mouth, and overlaying the said disc with a relatively thin flexible covering, whose circumferential margin is formed with a rolled convex flange or bib, which overlays and conforms to the beaded mouth of the bottle for shielding the mouth beyond the recess from germs and dirt. A further object is to provide simple means for binding the disc and cover together as one part, for facilitating applying and removing the closure, each of the said parts performing its own peculiar function, and the union of said parts tending to enhance the effectiveness of the sealing due to the intimate relation of the contiguous portions of said members, wherein the disc and the corresponding portion of the cover supplement and reinforce each other and obviate all danger of the closure being accidentally unseated. And a further object is to generally improve and simplify the construction, and to speed-up and cheapen the production of bottle closures of the class.

This invention relates particularly to improvements in the bottle closures shown and described in Patents Nos. 1,101,687, 1,460,269 and 1,597,130.

I attain these objects by the means set forth in the detailed description which follows, and as illustrated by the accompanying drawing, in which—

Figure 1 is a central vertical section, showing the closure applied to a milk bottle. Fig. 2 is a top plan view of the closure. Fig. 3 is a similar sectional view, showing a modified arrangement of the members of the closure. Fig. 4 is a top plan view of the same. Fig. 5 is a bottom face view of the disc of Figs. 3 and 4; showing an adhesive by which the cover and disc are connected as one part.

Referring to Figs. 1 and 2 of the drawing, 2 represents the neck of a bottle, and 3

the mouth, which is surrounded by a bead or lip 4, the latter together with an annular ledge or seat 5 comprising the usual annular recess 5', which receives and supports the cap or closure, as 6, by which the mouth is sealed. The closure 6 is preferably composite, and consists of a plane disc 6', which rests upon the ledge 5, its diameter preferably being such that force is required to effect the firm seating of the disc, and at the same time dispose its periphery in sealing contact with the vertical shoulder or wall 4' of the recess. Upon the disc 6' is mounted a circular cover 6^a, consisting preferably of relatively thin flexible fiber, such for example, as pulp-board, and the like, the said cover comprising a plane disc-shaped medial portion 6^b, of substantially the same diameter as the disc 6', which overlays the said disc, and may be permanently secured thereto, by light wire staples 7. The proper clinching of the staples tends to draw and hold the two discs intimately and rigidly together, as one part. The central portion 6^b of the cover is skirted by an annular flange 6^c, the latter preferably being rolled or molded convex to conform to the flare of the mouth 3, the said flange being of such breadth as to overlay and shield the entire top as well as the inner face of the bead 4, from dirt and germs, during the interval between the filling and the dispensing of the contents of the bottle. Ordinarily, the disc 6' alone will produce a satisfactory sealing of the bottle mouth, but in order to do this effectively, the said disc must be relatively thick and inflexible, in order to withstand rough handling, without being loosened or displaced sufficiently to allow the contents of the bottle to escape, or germs to enter the neck 2. The cover 6^a, it will be understood, may be applied to the bottle mouth alone, for effectively shielding the lip 4, provided fiber of suitable thickness and pliability is employed, for enabling the cover to be properly seated in the recess of the mouth, and rendered self-supporting. In either case, the extra weight of the material and the extra time and means required to produce and apply the said parts separately, greatly increases the cost of manufacture and tends to curtail production and limit the use of the detached parts. The present invention has for its particular object to provide a combined closure and sanitary protector for

bottle mouths, all parts of which may be made of relatively light-weight fiber, which when fabricated into one part, is considerably lighter than the combined weight of the detached members. This materially quickens and cheapens the production besides reducing the capping work to a single operation. Furthermore when the parts are rigidly bound together, as shown, the relatively light primary sealing member 6' becomes reinforced to such extent that the central portion of the closure is really thicker and stiffer, and therefore produces a more substantial and effective sealing, than many of the closures heretofore used. Furthermore, by combining the relatively light-weight disc and cover, in the manner shown, not only greatly facilitates the packing, applying and removing of the closure, but each of said parts tends to reinforce and supplement the other, for producing a highly efficient and sanitary closure, which will withstand rough handling, and may be exposed to dust, dirt and other deleterious elements, without danger of the contents of the container escaping, or the pouring-mouth of the bottle being rendered unsanitary. The closure 6 may be readily and quickly removed for dispensing the milk, or other contents, by prying upwardly the convex flange 6^c, either with a knife or by the use of the fingers.

In Figs. 3, 4 and 5, the order or arrangement of the disc 8 and the cover 8', is reversed. That is to say, the disc 8 is mounted upon the depressed plane portion 8^a of the cover, to which it may be permanently secured, by any suitable adhesive, as indicated at 9 (see Figs. 3, 4 and 5). In this modified closure the primary sealing of the contents of the bottle 2', is effected by the direct contact of the portion 8^a with the ledge 5, supplemented by similar contact of the periphery of said portion, with the shoulder 4' of

the recess, the depth of the seal at this point 45 being increased, and the sealing being rendered more effective by the thickness of the disc 8, the latter preferably being of such diameter as to effect a close and tight joint with the base of the flange 8^b of the cover, 50 when the closure is applied by the capping machine. By adhesively uniting the parts 8 and 8', as shown and described, these members may be handled as one part, and fiber of relatively light gage may also be employed 55 for producing the said members. The disc 8 and the cover 8' may follow the substantially same construction, and perform the same functions, as the corresponding parts of Figs. 1 and 2. 60

Having thus described my invention, what I claim, is—

A bottle closure comprising a thin and freely flexible member of uniform diameter throughout having a central substantially 65 flat portion and a curved annular portion formed to overlie the bead of a bottle mouth, a disk underlying the central portion of the member and being formed to seat on the ledge of the bottle mouth, said disk being 70 stiff and of greater thickness than that of the body and means to secure the disk to the central portion of the member with the entire area of the disk in intimate contact therewith and at points throughout and adjacent to the periphery of the disk consisting of a series of staples arranged in circular formation and disposed spaced from the center of the disk and adjacent the periphery thereof whereby upon lifting of the 80 curved annular portion of the member, the disk will be lifted from the ledge by power applied at a point adjacent to the disk periphery thereby to prevent tearing or distortion of the disk. 85

In testimony whereof I affix my signature.

WALLACE M. WEEKS.
